UNITED STATES PATENT OFFICE.

CHARLES G. JOHNSON, OF WEST SUPERIOR, WISCONSIN, ASSIGNOR OF ONE-HALF TO ALFRED PETTERSON, OF SAME PLACE.

TRUNK-LOCK.

SPECIFICATION forming part of Letters Patent No. 653,141, dated July 3, 1900.

Application filed August 28, 1899. Serial No. 728,805. (No model.)

To all whom it may concern:

Be it known that I, CHARLES G. JOHNSON, a citizen of the United States, residing at West Superior, in the county of Douglas and State of Wisconsin, have invented certain new and useful Improvements in Trunk-Locks; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in trunk-locks; and the object of the invention is to provide a cheap, strong, and neat trunk-lock which works on the principle of a permutation-lock, so that it needs no key for its operation. This object I attain by the novel construction and arrangement of parts illustrated in the accompanying drawings, in which—

Figure 1 is a front elevation of a portion of a trunk having my new lock applied to it. Fig. 2 is a back side view of the lock removed from the trunk. Fig. 3 is a substantially-central vertical section through Fig. 1. Figs. 4 and 5 are detail side views of the two dials by which the lock is opened and closed.

Referring to the various parts in the drawings by reference-numerals, 1 is the body, and 2 the cover, of a trunk to which my new lock is secured by the rivets 3, and consists of the lower and upper plates 4 and 5, secured, respectively, on the trunk and cover.

6 is a space in the upper plate to lighten it or save material.

7 are guides on the upper plate, adapted to guide in the pockets 8 in the lower plate 4, and thus bring the upper and lower plate in line and resist horizontal pressure against the cover. The pockets 8 I preferably make open at the inner side, so that in casting the plate no core will be needed.

The upper plate is provided in its lower portion with a deep notch 9, from which extend the internal notches or journals 10, in which rock the trunnions 11 of the locking-arm 12, which is normally held outward in an unlocked position from the lower plate 4

by the spring 13. The locking-arm 12 is provided on its inner side with the hook 14, which when the trunk is locked enters through the aperture 15 in the lower plate and through the slits or notches 16 and 17 in the edges of the two locking-disks 18 and 19, so that when one or both of the disks are turned with their notches away from the hook the latter is held in its locked position by the solid edge of the disks and can only be unlocked again by turning the disks till the two notches 16 and 17 register with the hook. The disk 18 is slightly sunk into the inner side of the plate 4 and is made hollow at its back side, so that it houses the disk 19, which is turned by the numbered, graduated, and at its edge knurled dial 20, located in the bevel-edged cavity 21 in the outer side of the lower plate 4 and connected with said disk by the tube 22, having the four-cornered end 22^X, entering a square hole in the disk. 23 is a smaller graduated and numbered dial provided with a central stem 24, which extends through the sleeve or tube 22 and fits with its square end 25 in the disk 19, in which it is retained by the pin 26. By means of the square holes in the disks they may be turned, each of them, in four different directions, and thereby change to eight different combinations.

The dials may have any desired number of the graduation-marks 27 and 28, and those may be marked with numerals or letters, or both.

In operation the predetermined marks on both dials which come in radial line with the notches 16 and 17 in the disks are both turned toward the mark "26" on the arm 12. This brings the notches in line with the hook 14, so that the arm 12 may be either closed or opened. In the latter act the spring 13 assists. The beveling 21 is to admit the fingers to get hold of the larger dial 20. The arm 12, it will be seen, folds into a groove or seat 26^X in the lower plate 4 and is provided with the shoulders 29, which engage below the shoulders 30 of the plate.

Having thus described my invention, what I claim as new, and desire to secure by Letters Patent, is—

1. A trunk-lock comprising in combination, an upper and a lower plate securable, respec-

tively, on the cover and the body of the trunk, the upper plate having a pivoted arm with a single hook or ward adapted to enter horizontally into the front of the lock when the arm hangs down, the lower plate having an aperture for said hook to pass through, and at its rear side a plurality of concentric locking-disks, and at its front side a plurality of graduated concentric operating-dials, each of which is secured by a shaft or sleeve to one of the locking-disks; said disks having each a notch in its edge for the hook to pass through and engage the rear of the disks when they are turned away from the opening and locking position; the front locking-disk having an annular flange projecting rearwardly flush with the rear side of the rear disk, substantially as set forth.

2. A trunk-lock comprising in combination an upper and a lower plate securable the former to the cover and the latter to the body of a trunk, the upper plate having a pivoted arm with a single locking-hook adapted to enter the lock from the front, the lower plate having an aperture for said hook, and a plurality of locking-disks arranged concentrically at the rear side of the plate, and provided with notches in their edges for the locking-hook to pass through and engage the rear of the disks, said disks having shafts or sleeves projecting forward through the plate and graduated operating-dials secured on them in front of the plate; said plates having the guides 7 and the pockets 8 adapted to engage each other; and a suitable mark on the lower

plate or on the locking-arm to indicate the unlocking position of the dials according to predetermination, substantially as set forth.

3. In a trunk-lock, the combination with two lock frame-plates adapted to be secured one to the trunk proper, and the other to the trunk-cover, of a pivoted locking-arm suspended from the upper plate and having the angular side shoulders 29, and the two plates being grooved to receive the arm flush with their outer surface, and the lower plate having the angular shoulders 30 engaging the shoulders 29, and means for locking said arm in said groove, substantially as and for the purpose set forth.

4. In a permutation-lock, the combination with two concentric locking-disks, both having a notch in their edge, of a single locking-hook adapted to engage the rear of the disks and to pass through the notches in a direction parallel to the axis of the disks when locking and unlocking take place; said disks being one smaller than the other and sunk into a cylindrical cavity in the side of the larger disk so that the two disks present an even surface to the hook or ward, and suitable marked dials for turning the disks, substantially as set forth.

In testimony whereof I affix my signature in presence of two witnesses.

CHARLES G. JOINSON.
